(57) **CLAIM**

The ornamental design for a watch as shown and described.

DESCRIPTION

FIG. 1 is a front, left perspective view of a watch showing our new design according to a first embodiment, with the watch bands in a folded configuration;

FIG. 2 is a rear, right perspective view thereof;

FIG. 3 is a left view thereof;

FIG. 4 is a right view thereof;

FIG. 5 is a bottom view thereof;

FIG. 6 is a top view thereof;

FIG. 7 is a front view thereof;

FIG. 8 is a rear view thereof;

FIG. 9 is a bottom view thereof, with the watch bands removed for ease of illustration;

FIG. 10 is a top view thereof with the watch bands removed for ease of illustration;

FIG. 11 is a rear view of thereof with the watch bands removed for ease of illustration;

FIG. 12 is a front, left perspective view of the watch showing our new design according to a second embodiment;

FIG. 13 is a rear, right perspective view thereof;

FIG. 14 is a left view thereof;

FIG. 15 is a right view thereof;

FIG. 16 is a bottom view thereof;

FIG. 17 is a top view thereof;

FIG. 18 is a front view thereof; and,

FIG. 19 is a rear view thereof.

The ornamental design which is claimed is shown in solid lines in the drawings. The broken lines in the figures illustrate portions of the watch that form no part of the claimed design.

1 Claim, 18 Drawing Sheets
